UNITED STATES PATENT OFFICE.

CHARLES C. RUSSELL, OF GREENFIELD, MASSACHUSETTS.

SCREW-PLATE.

1,074,466.

Specification of Letters Patent. Patented Sept. 30, 1913.

Application filed December 14, 1912. Serial No. 736,887.

To all whom it may concern:

Be it known that I, CHARLES C. RUSSELL, a citizen of the United States, residing at Greenfield, in the county of Franklin and State of Massachusetts, have invented certain new and useful Improvements in Screw-Plates; and I do hereby declare the following to be a full, clear, and exact description of the invention, such as will enable others skilled in the art to which it appertains to make and use the same.

My invention relates to screw plates, and it consists in the constructions, combinations and arrangements herein described and claimed.

The object of my invention is to provide an improved screw plate adapted to be readily opened upon the completion of a thread; thereby saving time and avoiding wear on the dies and injury to the thread incident to running the dies back over a completed thread.

In the accompanying drawings forming a part of this application and in which similar reference symbols indicate corresponding parts in the several views:—Figure 1 is a rear face view, partly broken away, illustrating one embodiment of my invention; Fig. 2 is a side view at the left of Fig. 1; Fig. 3 is a side view at the right of Fig. 1; and Fig. 4 is a detail axial section, on a reduced scale, through the guide, die members and stock.

Referring to the drawings, 1 and 2 indicate the two half-sections of a stock, which are pivotally connected at 3 and provided with extensions 4 and 5. A cam 6 is pivoted at 7 in the extension 4 in position to engage a hardened wear plate 8 on the extension 5, for forcing the two stock sections apart. The pivoted cam 6 is provided with a threaded shank 9 adapted to swing through a slot 10 in the extension 5, and carrying a thumb nut 11 for engaging the outer face of said extension 5 to firmly clamp the stock sections together. A pair of die members 12 are rotatably secured on a guide 13 by a cup-headed screw 14, and a screw 15 is threaded in said guide 13 and provided with a tapered head engaging between said die members for adjusting the latter. The guide 13 is seated on inward projections 19 on

the stock sections 1 and 2; said stock sections being provided with lugs 17 engaging slots 18 in the peripheral surfaces of the die members 12, for swinging said die members about said securing screw 14 upon separation of the stock sections.

It will be obvious that a split elastic or spring stock could be substituted for the pivotally connected stock sections, and that a screw device could be employed for opening the stock.

I have illustrated and described preferred and satisfactory constructions, but changes could be made within the spirit and scope of my invention.

I claim:—

1. In a screw cutting device, a stock comprising separable sections, means for detachably clamping said sections together, a pair of die members hinged together, and means on said stock sections for engaging said die members to open the latter upon separation of said stock sections.

2. In a screw cutting device, the combination of a stock comprising separable sections, means for detachably clamping said sections together, a pair of die members provided with peripheral slots and hinged together, a screw provided with a tapered head engaging between said die members for adjusting the latter, and lugs on said stock engaging said slots in said die members for opening the latter upon separation of said stock sections.

3. In a screw cutting device the combination of a stock comprising separable sections, means for detachably connecting said sections together, a guide seated on said stock sections, a pair of dies rotatably secured on said guide, a screw threaded in said guide and provided with a tapered head engaging between said die members for adjusting the latter, and means on said stock sections for engaging said die members to open the latter upon separation of said stock sections.

In testimony whereof, I affix my signature, in presence of two witnesses.

CHARLES C. RUSSELL.
